SELF-LOCKING SASH BALANCE

Glenn B. Haas, Oak Harbor, Ohio, assignor to Formetal, Inc., Oak Harbor, Ohio; a corporation of Ohio

Application April 12, 1954, Serial No. 422,350

14 Claims. (Cl. 16—197)

This invention relates to builder's hardware and, in particular, to sash balances.

One object of this invention is to provide a self-locking automatically-releasing sash balance which is especially adapted for use with removable sliding sash windows in that it remains in its attained position when the sash is removed, regardless of the location where removal takes place; so that the sash may be replaced in its original position without having to touch the sash balance, which automatically reassumes its weight-balancing function upon contact with the replaced sash.

Another object is to provide a self-locking automatically-releasing sash balance of the foregoing character wherein the sash balance spring and substantially all of the sash balance mechanism is contained within an elongated tube placed at the side of the window frame or in the side of the sash itself, so that the sash balance occupies much less space than prior sash balances of the spring-wound drum-and-tape, as well as requiring less labor and skill in installation.

Another object is to provide a self-locking automatically-releasing sash balance adapted to be used with either wood or metal sashes, and wherein a single standard unit is adaptable to be inserted within various types of wood or metal sash guides or within a suitable groove in either the window frame or in the side of the sash itself, thereby simplifying manufacture and enabling one unit to be used for widely differing types of sash installations.

Another object is to provide a self-locking automatically-releasing sash balance of the foregoing character wherein locking is accomplished by a tilting locking member which is slidable relatively to the tube containing the balancing spring when the locking member is approximately perpendicular to the tube but which tilts into gripping engagement with the tube when it is released from engagement with the sash upon removal of the sash, the gripping engagement taking place either on the inner and outer walls of the tube or on the outer wall only.

Other objects and advantages of the invention will become apparent during the course of the following description of the accompanying drawings, wherein:

Figure 1 is a vertical section through a double-hung sliding sash installation equipped with an internally self-locking and self-releasing sash balance according to one form of the invention, wherein the sash balance is contained within a metal sash guide on one side of the window frame;

Figure 2 is a vertical section taken at right angles to the section of Figure 1, along the line 2—2 therein;

Figure 3 is a horizontal section taken along the line 3—3 in Figure 1;

Figure 4 is an enlarged fragmentary vertical section through the lower end of the sash balance and adjacent portion of the sash, showing the locking mechanism in its released position;

Figure 5 is an enlarged fragmentary horizontal section through the sash guide and sash balance of Figures 1 to 4

2

inclusive, with the sash removed and the locking mechanism in its locked position;

Figure 6 is a vertical section taken along the line 6—6 in Figure 5;

Figure 7 is a vertical section at right angles to the vertical section of Figure 6, taken along the line 7—7 in Figure 5;

Figure 8 is a side elevation of the locking plate carrier of the sash balance shown in Figures 1 to 7 inclusive, with the central portion omitted to conserve space;

Figure 9 is a front elevation, similarly shortened, of the locking plate carrier shown in Figure 8;

Figure 10 is a top plan view of the locking plate used in the sash balance of Figures 1 to 7 inclusive;

Figure 11 is a side elevation of the locking plate shown in Figure 10;

Figure 12 is a horizontal section in a plane similar to the plane of Figure 3, but showing a modification in which the metal sash guide is formed with a tubular portion containing the working mechanism of the sash balance, eliminating a separate tube;

Figure 13 is a similar horizontal section through a further modification wherein the sash balance is secured to the side of a plain wooden window frame and projects from it into a groove in the side of the sash;

Figure 14 is a similar horizontal section through a still further modification wherein the sash balance is mounted in a groove in the side of a plain window frame;

Figure 15 is a similar horizontal section through an additional modification wherein the sash balance is mounted within the metal window frame of double-hung removable metal sliding sash, on the resilient side thereof;

Figure 16 is a fragmentary front elevation of the lower portion of a modified sash balance, according to the invention, employing an externally-gripping locking plate, in its locking position;

Figure 17 is a side elevation, partly in vertical section, of the modified sash balance shown in Figure 16; and

Figure 18 is a horizontal section taken along the line 18—18 in Figure 17.

Removable double-hung sliding sash windows in recent years have been widely introduced in the building industry, and their use has facilitated the cleaning of windows as well as reduced drafts, heat losses and rattling.

In such windows, one of the vertical sash guides in the window frame is resiliently mounted, so as to be yieldable sufficient distance to permit the opposite side of the window sash to be removed from its stationary sash guide by pushing sidewise on the sash, thereby enabling the sash to be quickly and easily removed for cleaning or other purposes. In such installations, however, it is necessary to use a sufficiently stiff spring pressure against the yieldable sash guide to cause the sash guides and sash to frictionally grip one another to an extent sufficient to overcome the weight of the sash and prevent it from dropping, unless a sash balance is employed. Conventional sash balances, however, greatly complicate the use of removable sash windows since, if used, they require attaching and detaching the sash balance cord, cable, chain or tape every time the sash is removed, and require reconnecting it when the sash is replaced in the window frame. When the sash is removed in such an installation, however, the cord, cable, chain or tape flies upward

under the influence of the weight or spring attached to it, and must be pulled down and reconnected before the sash can be reinserted in its sash guide.

The present invention provides a spring sash balance which is mounted alongside the sash in the sash guide or window frame and has a spring of sufficient tension to counterbalance the weight of the sash, thereby requiring only light spring pressure against the yielding sash guide.

in order to remove the sash, since the springs associated with the yielding sash guide are no longer required to force the sash guide and sash together with a sufficient frictional force to hold the sash in its raised position. The sash balance of the present invention, moreover, merely engages the sash without requiring positive connection to the sash, the sash balance being provided with self-locking and self-releasing mechanism which goes into operation to automatically lock the sash balance in its attained position when the sash is removed, and to automatically release the sash balance to resume its balancing function when the sash is replaced. The sash balance spring is housed in an elongated metal tube with a slot in the front thereof through which a locking plate carrier projects and holds a tilting locking plate which instantly rocks and grips the tube to lock the carrier in its attained position when the sash is removed. When the sash is replaced, the locking plate is rocked in the opposite direction to release its grip upon the tube so that the balancing spring resumes its balancing function. The spring sash balance of Figures 1 to 15 inclusive employs an internally-gripping locking plate, whereas the modified spring sash balance of Figures 16 to 18 inclusive employs an externally-gripping locking plate.

Referring to the drawings in detail, Figures 1 to 3 inclusive show a double-hung sliding removable window sash installation, generally designated 10, consisting of upper and lower sliding sashes 12 and 14 slidably mounted in metallic sash guides 16 and yielding sash guides 17 set into elongated vertical recesses 18 and 19 respectively in the opposite side members 20 and 21 respectively of a window frame, generally designated 22. The window frame 22 has a sloping window sill 24 and a head or top member 26, the construction being shown in simplified or diagrammatic form for clarity of illustration. In the form shown in Figures 1 to 11 inclusive, the stationary sash guide 16 is of a special rolled cross-section whereas the yielding sash guide 17 is of conventional form, the details of which are beyond the scope of the present invention. For the purposes of the present disclosure, the yielding sash guide 17 (Figure 3), of which there are two disposed side by side to receive the upper and lower sashes 12 and 14, consists of a metal channel member of approximately E-shaped cross-section having a central guide portion 28 with longitudinally-spaced apertures 30 in which fastener cups 32 are inserted, the bottom of each fastener cup 32 being drilled to receive a fastener 34 seated in the side member 20. Adjacent and between the fastener cups 32 are longitudinally-spaced coil springs 36 which urge the yielding sash guide 17 into engagement with the window sash 12 or 14, the side edge portion 38 of which slidably engages the central guide portion 28.

The opposite or stationary sash guide 16 may, like the yielding sash guides 17, be formed in two separate units but, for purposes of simplicity, Figure 3 shows it as formed in the shape of a one-piece double-guide unit. The sash guide 16 is preferably rolled in a rolling mill or rolling machine from strip aluminum or other suitable sheet metal, and includes two sash guide channel portions 40 and 42 respectively (Figure 3) also of approximately E-shaped cross-section but with extended channel portions 44 and 46 depressed relatively to the channel portions 40 and 42 so as to snugly receive and house the self-locking sash balance, generally designated 50 according to the first form of the invention. The two guide channel portions 40 are spaced apart from one another, one receiving the upper sash 12 and the other the lower sash 14, and are interconnected by a bridge portion 52 which is drilled as at 54 to receive fasteners 56 for securing the stationary sash guide unit 16 to the window frame side member 20.

The self-locking and self-releasing spring sash balance 50 of Figures 1 to 11 inclusive is housed in an elongated metal tube 58 of approximately rectangular cross-section with a rectangular chamber 60 running from one end to

the other thereof and with an elongated slot 62 in the front wall 64 of the tube 58 (Figure 5). Thus the tube 58 is of approximately square C-shaped cross-section. The upper and lower ends of the tube 58 are drilled for the passage of fasteners 66 and 68, the upper fastener 66 also serving as an anchorage for the upper end of an elongated tension spring 70. The fasteners 66 and 68 secure the tube 58 and the channel portions 44 and 46 to the window frame side members 20.

The lower end of the tension spring 70 is hooked through a hole 72 in a locking plate carrier 74 (Figures 8 and 9) of a sash balance locking device, generally designated 76, which also includes a tilting or rocking locking plate 78. The carrier 74 is in the form of an approximately L-shaped metal plate or bar having a vertical arm 80 and a horizontal arm 82 with a notch 84 at their junction on their inner edges. The notch 84 has an upper edge 86 which is substantially perpendicular to the front edge 88 of the upper arm 80, the rearward edge 90 of the notch 84 and the lower portion 92 of the rearward edge 94 thereof being arcuate and approximately concentric with a neck portion 93 between them. The lower edge 96 of the notch 84 is inclined and converges toward the lower edge 98 of the lower arm 82, of which it forms part of the upper edge 100, the latter being substantially parallel to the lower edge 98. The upper edge portions 96 and 100 join one another at a ridge or fulcrum edge 102, which is nearer the front edge 103 of the arm 82 than the rear edge 90 of the notch 84. The front and rear edges 88 and 94 are also substantially parallel except for the arcuate lower edge portion 92.

The locking plate 78 (Figures 10 and 11), which cooperates with the locking plate carrier 74, is approximately rectangular in shape with a forward trigger portion 104 and a rearward portion 106 separated from one another by rectangular notches 108 extending inwardly toward one another from the opposite edges 110 of the locking plate 78. The rearward portion 106 of the locking plate 78 also has a larger rectangular notch 112 in its rearward edge 114 of sufficient width to loosely receive the neck portion 93 (Figure 5). The notches 108 are of slightly greater width than the thickness of the tube 58 (Figure 6) so that their opposite edges tightly grip the inner and outer surfaces of the front wall 64 of the tube 58 when the locking plate 78 is pulled into its tilted position by the spring 70 when the sash 12 or 14 is removed, but are of sufficient width to loosely and slidably pass along the front wall 64 (Figure 4) when the sash is replaced, and engages the locking plate 78. Thus the locking plate 78 tilts around the ridge 102 as a fulcrum. In order to receive and engage the locking plate 78, each sash 12 or 14 is provided with a rectangular notch 116 having an upper abutment wall or shoulder 118 perpendicular to its outer edge and consequently adapted to tilt the locking plate 78 around its fulcrum 102 into a position likewise perpendicular.

In the operation of the invention, let it be assumed that the lower sash 14 is raised a short distance above the sill 24 (Figure 1) with its abutment wall 118 tilting the locking plate 78 around its fulcrum 102 into the free-sliding perpendicular position of Figure 4. In this position the opposite sides of the notches 108 and the locking plate 78 do not engage the front wall 64 of the tube 58, so that the sash 12 or 14 may be raised and lowered freely while the spring 70 counterbalances the weight of the sash.

To remove the sash 14 from its position of Figure 1, the operator grasps the sash 14 in his hands and shifts it sidewise to the right (Figures 1 and 3), pushing the yielding sash guide 17 to the right, compressing the springs 36. This enables the edge portion 38 of the sash 14 to be withdrawn from the channel portion 42 of the stationary sash guide 16, so that the left-hand side of the sash 14 may be swung outward past the edge of the window frame 22,

permitting the sash 14 to be completely removed from the window frame 22.

The instant the shoulder 118 of the notch 116 of the sash 14 is disengaged from the locking plate 78, the locking plate carrier 74 is jerked upward by the tension spring 70, rocking the locking plate 78 around the fulcrum 102 off the perpendicular edge portion 100 and onto the inclined portion 96, causing the opposite edges of the notches 108 to bite into the front wall portions 64 of the tube 58 on opposite sides of the slot 62 (Figures 5, 6 and 7). The tube 58 is preferably made of a relatively soft metal, such as aluminum, to facilitate this biting action. When the locking plate 78 is thus tilted (Figure 1), it instantly halts the upward motion of the locking plate carrier 74 and holds the sash balance 50 in its attained position. After the sash 14 has been cleaned or otherwise treated, it is replaced by inserting its right-hand edge in the channel portion 28 of its respective yielding sash guide 17, whereupon the operator pushes to the right a sufficient distance to cause the sash guide 17 to yield sufficiently to permit its left-hand edge portion 38 to re-enter the sash guide channel 42 immediately above the locked location of the locking plate 78 which enters the notch 116 in the lower left-hand corner of the sash 14. The sash 14 either drops of its own weight or is pushed downward until the shoulder 118 at the top of the notch engages the forward portion 104 of the locking plate 78 and tilts it into its perpendicular position (Figure 4) around the fulcrum 102, the rearward portion 106 coming to a halt against the upper edge 86 of the notch 84. This releases the opposite edges of the notches 108 from their biting grips upon the front wall portions 64 of the sash balance tube 58, permitting the sash balance to move upward freely and resume counterbalancing the weight of the sash 14.

The modified removable sash installation, generally designated 119, shown in Figure 12 is similar in principle to the form of the invention shown in Figures 1 to 11 inclusive, except that the sash balance tube 58 is omitted, and the rearward channel portion 44 of the sash guide 16 is joined to the sash guide channel portion 40 by inwardly-turned reversely-bent edges 120 with a slot 122 between them. The combined thickness of each of the reversely-bent portions 120 is slightly less than the width of the side notches 108 of the locking plate 78, so that the latter slides freely when in its perpendicular position analogous to Figure 4, but bites into the outer and inner surfaces of the portions 120 when the sash is removed and the plate 78 is rocked by the upward pull of the spring 70. The operation of the modification of Figure 12 is otherwise the same as has been described immediately above.

The modified removable sash installation, generally designated 124, shown in Figure 13 employs the same sash balance 50 as has been described above in connection with Figures 1 to 11 inclusive, but the tube 58 is shown as fastened directly to the window frame side members 20 instead of being seated in a metal sash guide. In this modification, the sashes 12 and 14 are grooved as at 126 to slidably receive the tube 58, and the bottom of each groove 126 is provided with a notch 128 with an upper wall or shoulder 130 similar in position, location and function to the notch 116 with its shoulder 118 of Figure 4. The operation of the modified sash installation 124 is similar to that of the principal installation 10 and modified installation 119 previously described above and hence requires no repetition.

The modified removable sash installation, generally designated 132, shown in Figure 14 is similar to that of Figure 13, except that the tube 58 of each sash balance 50 is set into a groove 134 in the window frame side member 20 instead of projecting from it as in Figure 13 or being mounted within a metallic sash guide as in Figures 1 to 12 inclusive. The sashes 12 and 14, as in Figure 1, are provided with notches 116 with upper abutment walls or shoulders 118 and for the same purpose. The opera-

tion of the modification 132 is otherwise the same as that of Figures 1 to 11 inclusive and hence requires no repetition.

The modified removable sash installation 140 shown in Figure 15 is also similar in principle to the foregoing forms of the invention, except that the invention has been applied to a removable double-hung metallic sash window, generally designated 142, consisting of metal-framed upper and lower sashes 144 and 146 mounted in sash guide channel members 147 and 148 respectively. The guide channel member 148 has guide channels 150 and 152 side by side for receiving the right-hand edges of the sashes 144 and 146. The guide channel member 147 has deeper channels 154 and 156 side by side for receiving the opposite edges of the upper and lower sashes 144 and 146 and the two sash balances 50, both of which are loosely mounted on their respective fasteners 66 and 68 (Figure 1) so as to be freely movable laterally under the urge of coil springs 158 and 160 respectively, a separate anchorage being provided, if necessary, for the spring 70. The adjacent sides of the upper and lower sashes 144 and 146 are notched as at 162 in a manner similar to the notches 116 in the lower left-hand corners of the wooden sashes of Figure 1, and providing abutment shoulders or walls 164 similar in purpose and action to the abutment shoulder or wall 118.

The operation of the metallic removable window sash installation 142 of Figure 15 is also generally the same as in the form of the invention shown in Figures 1 to 11 inclusive, hence likewise requires no repetition. In this instance, however, each sash is pushed to the left in order to disengage it from the guide channel 150 or 152, compressing the spring 158 or 168 and shifting the sash balances 50 to the left so as to permit the sashes 144 and 146 to be removed. Locking takes place in the same manner as described above in connection with Figures 1 to 11 inclusive when the sash 144 or 146 is disengaged from its respective locking plate 78.

The modified sash balance, generally designated 170, shown in Figures 16 to 18 inclusive is similar in principle to the sash balance 50 of Figures 1 to 15 inclusive except that it employs an externally-gripping locking plate 172 instead of the partly external and partly internal locking plate 78 of Figures 1 to 15 inclusive, which for convenience and conciseness has been designated internal locking plate 78. The tube 174 which houses the spring 176 and locking plate carrier 178 is of slightly different cross-section than the tube 58 in that it has parallel front and rear walls 180 and 182, an elongated front wall slot 183, parallel forward side walls 184 and converging corner side walls 186 (Figure 18). The locking plate carrier 178 is also L-shaped, but of slightly different form, in that it has a vertical arm 188 encircled by the spring 176 and a horizontal arm 190 which has upper and lower notches 192 and 194 respectively serving as anchorages for the lower end of the spring 176. The horizontal arm 190 has an upper edge 196 which engages the forward portion 198 of the locking plate 172. The locking plate 172 has a notch or opening 200 extending from its rearward edge 202 toward its forward portion 198. The opening 200 is of similar cross-section to the tube 174, but slightly larger so as to permit free sliding of the locking plate 172 relatively to the tube 174 when the former is perpendicular to the latter by reason of the engagement of the window sash therewith. For this purpose, the opening 200 has a forward edge 204, parallel side edges 206, and converging corner edges 208.

The operation of the modified sash balance 170 is similar in principle to that of the sash balance 50 described above, except that the locking plate 172 grips the outside of the tube 174 rather than partly inside and partly outside as in the case of the sash balance 50. When the sash is in position in its sash guides with its lower portion engaging the locking plate 198, the latter is forced downward against the perpendicular upper edge 196 of the arm

190, causing the locking plate 172 to assume a position perpendicular to the tube 174 and consequently permitting the locking plate 172 to slide freely upward or downward along the tube 174. When, however, the sash is removed, the spring 176 jerks the L-shaped carrier 178 upward, rocking the locking plate 172 so that its forward inner edge 204 bites into the outside surface of the forward wall 180 of the tube 174 and the converging internal corner edges 208 bite into the converging corner walls 186 of the tube 174, causing instant locking to take place.

What I claim is:

1. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion.

2. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said locking member comprising a notched plate supported by the projecting portion of said carrier.

3. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger por-

tion, said carrier being approximately L-shaped with horizontal and vertical arms and said locking member comprising a notched plate supported by the horizontal arm of said carrier.

4. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said carrier being approximately L-shaped with horizontal and vertical arms and said locking member comprising a notched plate supported by the horizontal arm of said carrier, with the opposite sides of the notch gripping engageable with spaced portions of said housing in the tilted position of said locking member.

5. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said carrier being approximately L-shaped with horizontal and vertical arms and said locking member comprising a notched plate supported by the horizontal arm of said carrier.

6. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger por-

tion, said carrier being approximately L-shaped with horizontal and vertical arms with a recess disposed at the junction of its horizontal and vertical arms and said locking member comprising a notched plate supported by the horizontal arms of said carrier, with an aperture therein receiving the vertical arm of said carrier and with an edge adjacent said aperture engageable with a side of said recess in the unlocked position of said locking member.

7. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said carrier being approximately L-shaped with horizontal and vertical arms with an upper edge portion of the horizontal arm thereof inclined downwardly toward its junction with the vertical arm thereof and said locking member comprising a notched plate supported by the horizontal arm of said carrier.

8. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said carrier being approximately L-shaped with horizontal and vertical arms with an upper edge portion of the horizontal arm thereof inclined downwardly toward its junction with the vertical arm thereof and said locking member comprising a notched plate supported by the horizontal arm of said carrier, said carrier having a recess disposed at said junction and said locking member having an aperture therein receiving the vertical arm of said carrier and with an edge adjacent said aperture engageable with a side of said recess in the unlocked position of said locking member.

9. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored

at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted

10 to tilt into gripping engagement with said housing in response to the disengagement of said sash from said trigger portion, said carrier being approximately L-shaped with horizontal and vertical arms with a forward upper edge portion of the horizontal arm thereof substantially horizontal and with a rearward upper edge portion of said horizontal arm inclined downwardly toward its junction with the vertical arm thereof and said locking member comprising a notched plate supported by the horizontal arm of said carrier.

20 10. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the

25 lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger

30 35 40 portion, said carrier being approximately L-shaped with horizontal and vertical arms with a forward upper edge portion of the horizontal arm thereof substantially horizontal and with a rearward upper edge portion of said horizontal arm inclined downwardly toward its junction with the vertical arm thereof and said locking member comprising a notched plate supported by the horizontal arm of said carrier and with a pivot at the junction of said forward portion and said inclined rearward portion of said horizontal arm.

50 11. A resilient sash balance for removable sliding sash windows which is automatically locked in its tensioned condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said locking member comprising a plate with an aperture therein configured to slidably receive said housing and extend around the major portion thereof.

55 60 65 70 75 12. A resilient sash balance for removable sliding sash windows which is automatically locked in its tensioned

condition in response to sash removal at a given location and automatically released in response to sash replacement and return to said given location, said sash balance comprising an elongated spring housing adapted to be secured to the window frame adjacent the sash and having an elongated opening in a side wall thereof, an elongated resilient element disposed in said housing and anchored at its upper end, a locking member carrier connected to the lower end of said resilient element and having a portion projecting through said opening, and a locking member tiltably mounted on said projecting portion and having a trigger portion projecting beyond said pivot into the path of travel of said sash for engagement thereby, said locking member having gripping portions adapted to slide freely relatively to said housing in response to the engagement of said trigger portion by said sash and adapted to tilt into gripping engagement with said housing in response to the disengagement of said sash from said trigger portion, said locking member comprising a plate with an aperture therein configured to slidably receive said housing and extend around the major portion thereof, said locking member having forward and rearward edge portions adjacent said aperture adapted to gripingly engage the forward and rearward walls respectively of said housing in response to the tilting of said locking member.

13. A combination self-locking sash balance and sash guide for sliding sash windows comprising an elongated sash guide member of sheet material having a channel portion therein adapted to slidably receive said sash, and a tubular extension portion disposed rearwardly of said channel portion with an elongated opening therebetween having an inwardly-projecting locking edge; an elongated resilient element disposed in said extension portion and anchored at its upper end, a locking member carrier connected to the lower end of said resilient element and having a portion projecting through said opening, and a locking member tiltably mounted on said projecting portion and having a trigger portion projecting into the path of travel of said sash for engagement thereby, said locking

40

member having gripping portions adapted to slide freely relatively to said locking edge in response to the engagement of said trigger portion by said sash and adapted to tilt into gripping engagement with said locking edge in response to the disengagement of said sash from said trigger portion.

14. A combination self-locking sash balance and sash guide for sliding sash windows comprising an elongated sash guide member of sheet material having a channel portion therein adapted to slidably receive said sash, and a tubular extension portion disposed rearwardly of said channel portion with an elongated opening therebetween having an inwardly-projecting locking edge; an elongated resilient element disposed in said extension portion and anchored at its upper end, a locking member carrier connected to the lower end of said resilient element and having a portion projecting through said opening, and a locking member tiltably mounted on said projecting portion and having a trigger portion projecting into the path of travel of said sash for engagement thereby, said locking member having gripping portions adapted to slide freely relatively to said locking edge in response to the engagement of said trigger portion by said sash and adapted to tilt into gripping engagement with said locking edge in response to the disengagement of said sash from said trigger portion, said locking member comprising a notched plate supported by the projecting portion of said carrier.
